Attorney

UNITED STATES PATENT OFFICE.

ALEXANDER MCKELLAR, OF GREENOCK, SCOTLAND.

MEANS FOR FACILITATING THE WITHDRAWAL OF CIGARETTES OR THE LIKE FROM THEIR CASES.

1,347,816.

Specification of Letters Patent.

Patented July 27, 1920.

Application filed June 12, 1919. Serial No. 303,646.

To all whom it may concern:

Be it known that I, ALEXANDER MCKELLAR, of 27 Cathcart street, Greenock, Scotland, watchmaker and jeweler, have invented certain new and useful or Improved Means for Facilitating the Withdrawal of Cigarettes or the like from Their Cases, of which the following is a specification.

My invention relates to improvements in cigarette and cigar cases of the type where a frame is provided inside, on which the cigarettes or cigars are carried and on the opening of which the frame assumes an upright or vertical position, and the object of my invention is to simplify and cheapen the construction of such as well as to prevent the cigarettes or cigars being in any way damaged as they are so liable to be where springs are employed.

The invention consists in the introduction of a magazine or independent container composed of a light metal framework for holding the cigarettes or the like in position within the case. The cigarettes or the like are placed in two rows within the magazine with the free ends of one row slightly in advance of its adjacent row. The magazine is hinged to the case. The pin which connects the two leaves or members of the case at the joint also passes through eyes of a partition plate forming an extension of the magazine. A pair of jointed levers after the manner of toggle joints connects the rear portion of the magazine to the inner edge of the two leaves of the case in such a manner that when the case is opened the magazine automatically assumes an erect position, presenting unobstructedly the ends of the cigarettes for easy withdrawal.

In order that my invention may be properly understood and readily carried into effect, I have hereunto appended one sheet of drawings, of which—

Figure 1 is a perspective view of the case for containing cigarettes and the like made in accordance with and embodying my invention with the case opened and the cigarettes presented for withdrawal.

Fig. 2 is a section cutting through one of the leaves of the case taken on the line *a, b*, Fig. 1, and showing the magazine in side elevation and the case in the opened position.

Fig. 3 is a longitudinal section of the same, while the dotted lines represent the case closed, drawn to an enlarged scale, and all hereafter more fully referred to and described.

Referring to the drawings, A and B represent the two leaves or sides of the case. C is the joint or hinge. D is the magazine consisting of a very light metal framework having rear sides, canopy and bottom E, F, G and H. The cigarettes being exposed, their free ends present themselves for withdrawal. A pair of jointed levers have their vertical ends I, J, pivotally attached to the rear external wall E of the magazine and their horizontal ends K, L, pivotally attached, the one K to the leaf or side A, and the other L to the leaf or side B of the case; these levers are fulcrumed at M and N. A partition plate O forming a downward extension *O'* of the central plate aforesaid of the magazine is pivotally connected to the hinge joint C of the case, Figs. 2 and 3. The magazine is formed of two rear compartments Q, R. The compartment Q has a false bottom or termination S. Due to this arrangement the cigarettes or the like in the row T protrude farther from the magazine in the horizontal plane than in the row U, Figs. 1 and 2. The opening of the case to the jointed levers I, J, K, L, aforesaid exerts a uniform strain on the magazine, bringing it into the central position as seen. The usual elastic retaining band V is employed.

Claims:

1. In the means for the withdrawal of cigarettes and the like from their cases, a magazine composed of light metal, rear wall part lateral sides, canopy and bottom, a central partition plate constituting two chambers or compartments of unequal length, said plate having a downward extension in order to connect it conjointly with the hinge of the case, jointed levers connected each with the rear wall of magazine, and one to one leaf of the case, and the other to the opposite leaf, operating substantially in the manner and for the purposes hereinbefore described and shown on the drawings.
2. A cigarette case comprising a pair of leaves hingedly connected together, a magazine pivotally connected to the pivot axis of

the hinge connection between the leaves, a pair of levers pivotally connected to one end of the magazine, and a pair of levers pivotally connected at their outer ends to the said leaves, the inner ends of the last named levers being pivotally connected to the first named levers.

In witness whereof I affix my signature in presence of two witnesses.

ALEXANDER McKELLAR.

Witnesses:

JOHN LIDDLE,

JOHN FRAIN LIDDLE.
